CLAIM

The ornamental design for a charger base for battery
operated flashlight or the like, as shown and described.

DESCRIPTION

FIG. 1 is a front, top and right-side perspective view of
a charger base for battery operated flashlight or the like
showing our new design;

FIG. 2 is a top plan view thereof;

FIG. 3 is a right-side elevational view thereof;

FIG. 4 is a left-side elevational view thereof;

FIG. 5 is a bottom plan view thereof;

FIG. 6 is a front elevational view thereof; and

FIG. 7 is a rear elevational view thereof.

FIG. 1

FIG. 2

FIG. 3

FIG. 4

FIG. 5

FIG. 6

FIG. 7
